PETROLEUM PROSPECTING

John D. Douros, Jr., and Richard L. Raymond, Wilmington, Del., assignors to Sun Oil Company, Philadelphia, Pa., a corporation of New Jersey
No Drawing. Filed Feb. 14, 1961, Ser. No. 89,100
3 Claims. (Cl. 195—103.5)

This invention relates to a biological method for prospecting for petroleum deposits which involves the use of serological techniques to obtain indicia as to the proximity of an underground petroleum reservoir.

Methods of prospecting for petroleum have been proposed heretofore wherein samples of earth from selected sites have been analyzed in various ways to indicate whether hydrocarbons or products resulting from bacterial decomposition of hydrocarbons are present. It has been postulated that hydrocarbon gases migrate through the earth from subterranean petroleum reservoirs and hence are present in the earth near the surface in the vicinity of petroleum deposits. It has proved difficult, however, to make reliable determinations of hydrocarbon content of soil samples due to the minute amount that may be present.

In soil subject to emanation of hydrocarbons from a petroleum deposit, microorganisms are generally present which consume or feed upon the hydrocarbon material. Accordingly it has been proposed to subject soil samples in the laboratory to an atmosphere containing a hydrocarbon gas, e.g. ethane, under growth conditions to allow the hydrocarbon-consuming microorganisms to multiply if any are present, and thereafter determine the extent of growth or the rate of consumption of the hydrocarbon. These values have been taken as indicia of the proximity of petroleum deposits with respect to the sampling location. Such procedures, however, have the drawback of being tedious and time-consuming, and the progress that can be made in running a prospecting survey over a wide area by such methods is slow.

The present invention provides an improved method of petroleum prospecting, whereby the presence of a hydrocarbon-consuming microorganism in soil samples can be rapidly determined. The method utilizes serological techniques for determining the presence or absence of a selected type of hydrocarbon-consuming microorganism and also the concentration thereof in the sample. The method is so readily performed that it is possible for a person to make several hundred soil tests in a single day.

In practicing the invention an antiserum is prepared which is specific toward any particular hydrocarbon-consuming microorganism which is known to be prevalent in soil subject to seepage of petroleum hydrocarbon gases. It is preferred that the antiserum be specific for *Mycobacterium paraffinicum*, since this type of bacteria is practically universally present in soil which is subject to continuous contact by the paraffin hydrocarbon gases. However, the antiserum can be specific for any other microorganisms that can feed on the gaseous paraffin hydrocarbons, for example, *Agrobacterium ethanicas*, *Bacterium hidium*, *Methanomonas methanica* and *Bacillus ethanicas*. Soil samples are collected from selected locations and a small amount of each sample is allowed to incubate for a time with a small volume of the antiserum. The incubated antiserum is then filtered from the soil and serologically tested at various dilutions with a culture of the microorganism which is an antigen for the antibody of the serum. If no reaction is obtained, this means that the soil had removed the antibody from the serum and hence that the soil contained the hydrocarbon-consuming microorganism. On the other hand, if heavy coagulation is observed, the absence of the

2

microorganism in the soil sample is indicated. The test can be done under specific conditions that can be compared with a standardized control test and the concentration of the microorganism thereby can be ascertained.

5 Hence an area can be mapped in terms of the quantities of the hydrocarbon-consuming microorganism present in the soil so as to indicate where a petroleum deposit likely is to be found.

The antiserum for use in practicing the invention is prepared by conventional biological techniques utilizing any suitable animal such as rabbit, hamster, chicken, horse or monkey. A culture of the microorganism, preferably *Mycobacterium paraffinicum*, is grown in a hydrocarbon-containing atmosphere which hydrocarbon 15 preferably is ethane, and the microorganism is rendered avirulent in any suitable manner such as by heat killing, formalizing, phenolizing or attenuation. The animal is then injected with the avirulent microorganism over a period of several days. Preferably the first injection is 20 subcutaneous and is followed by three or four intravenous injections on successive days. On about the sixth day the animal's blood will contain the desired antibodies and a quantity of it can be withdrawn. The blood is allowed to clot and stand at room temperature for at least three hours, and the serum is then decanted. It may be desirable to inactivate the serum at 56° C. for 45 minutes in order to destroy complement since the bacterial cells may be lysed in some instances. The serum can be stored under refrigeration at 0° C. The 30 titer of the antiserum can be determined by dilution tests in conventional manner.

In treating the soil sample only small amounts of the soil, e.g., 0.1 gram, and of the antiserum, e.g., 2-5 ml., need be used. The antiserum wash and the soil sample 35 are mixed and allowed to incubate for at least one hour at room temperature. The mixture may, if desired, be stored overnight at 4° C. The incubated antiserum is then filtered from the soil and is ready for serological testing.

Any of the known serological tests can be used for determining the presence, absence or the amount of antibody remaining in the incubated antiserum. Tests known as neutralization, agglutination, precipitin and complement fixation can be used, with neutralization being the preferred procedure. In general these involve admixing the antiserum with a normal saline preparation of the hydrocarbon-consuming bacteria (either virulent or avirulent) in a series of standard dilutions and observing the reaction. In cases where quantitative values are desired, comparisons can be made with standard control tests in which a known number of bacteria are reacted with various dilutions of the antiserum. Description of the various serological methods used in microbiological work are available in various texts, for example, by W. C. Boyd, "Fundamentals of Immunology," 3rd edition (1956), and hence need not be described in detail here.

The invention can also be practiced by subjecting each 60 soil sample to a plurality of tests carried out in the above-described manner but using several different antisera corresponding to different species of hydrocarbon-consuming microorganisms. This is generally not necessary, however, in view of the wide prevalence of *Mycobacterium paraffinicum* in hydrocarbon-containing soils. Hence tests made only with antiserum prepared by means of this type of microbe are sufficiently reliable to indicate whether a soil sample has been continuously subjected to a hydrocarbon-containing atmosphere and thus whether petroleum is probably deposited near the sampling site.

70 We claim:

1. Method of biological prospecting for petroleum deposits which comprises collecting soil samples from se-

lected locations; incubating each soil sample with an anti-serum, said antiserum having been prepared by inoculating an animal with an avirulent microorganism of a type capable of consuming gaseous petroleum hydrocarbon to form antibodies in the animal's blood stream and separating the antiserum from the blood; separating the soil sample from the incubated antiserum; and serologically testing the incubated antiserum with said microorganism to ascertain whether such microorganism was present in the soil as an indicium of the proximity of a

petroleum deposit with respect to the sampling location.

2. Method according to claim 1 wherein said microorganism is *Mycobacterium paraffinicum*.

3. Method according to claim 1 wherein said serologically testing involves ascertaining the concentration of said microorganism in the soil.
